United States Patent Office

Des. 203,664
Patented Feb. 8, 1966

203,664

MOBILE SERVICE STATION

Raymond C. Dietz, 1000 S. Main, Borger, Tex.

Filed July 30, 1964, Ser. No. 81,079

Term of patent 7 years

(Cl. D14—3)

FIG. 1

FIG. 2

FIG. 3

FIG. 4

FIG. 5

FIGURE 1 is a side view of a mobile service station showing my new design;

FIGURE 2 is a perspective view thereof showing the side and rear;

FIGURE 3 is a rear perspective view thereof;

FIGURE 4 is a perspective view of the left side of the vehicle; and

FIGURE 5 is a front perspective view thereof.

The dominant features of my design reside in the portions shown in full lines.

I claim:

The ornamental design for a mobile service station, as shown and described.
